UNITED STATES PATENT OFFICE

127,975

DESIGN FOR A WRIST BAG

Laura M. Schneider, New York, N. Y.

Application November 20, 1940, Serial No. 96,697

Term of patent 14 years

To all whom it may concern:

Be it known that I, Laura M. Schneider, a citizen of the United States, residing at New York city, county of New York, and State of New York, have invented a new, original, and ornamental Design for Wrist Bags, of which the following is a specification, reference being had to the accompanying drawing, forming part thereof.

Fig. 1 is a perspective view of wrist bags, showing my new design.

Fig. 2 is an end elevational view thereof.

I claim:

The ornamental design for a wrist bag, as shown.

LAURA M. SCHNEIDER.
